ATTORNEY.

UNITED STATES PATENT OFFICE.

JAMES W. HUGHES, OF CAMDEN, NEW JERSEY.

BODY-REST FOR MUSICAL INSTRUMENTS.

No. 920,144.

Specification of Letters Patent.

Patented May 4, 1909.

Application filed August 7, 1905. Serial No. 272,997.

To all whom it may concern:

Be it known that I, JAMES W. HUGHES, of Camden, county of Camden, and State of New Jersey, have invented an Improvement in 5 Body-Rests for Musical Instruments, of which the following is a specification.

Much difficulty has been experienced by musicians in the use of body rests for violins and the like. It is essential that such devices should enable the instrument to be held 10 in proper position and with sufficient firmness without discomfort caused by friction or undue pressure upon the chin or shoulder. It is also desirable that such rests should be 15 adaptable to instruments of different sizes and to the physical peculiarities of the musician.

It is one of the objects of this invention to provide a chin rest for violins and the like, 20 which may be easily adjusted to suit the size of the instrument, and which will be suited to practically all persons, and will adapt itself to differences in the conformation of the chin, so that it may be used with perfect 25 comfort and will insure the instrument being held firmly and in proper position.

My invention also includes improvements in the devices for applying the rest to the instrument and enabling it to adjust itself to 30 the size and shape thereof.

In the drawings: Figure 1 is a perspective view illustrating the rest applied to a violin; Fig. 2 is a front elevation of the detached clamp; Fig. 3 is a rear elevation of the same; 35 Fig. 4 is an inverted plan view of the base-plate of the rest, and Fig. 5 is a transverse vertical section, enlarged, of the rest and clamp.

a is the base-plate of the rest, which is 40 preferably of kidney shape and may be made of any suitable material. I have found aluminum excellently adapted for it.

On one side of the under surface of the base-plate is a rib *a'*, to which the bracket-piece *b* is secured by the angular flange *b'*.

The lower face of the plate *a* at one end is offset as at *a''* to permit the plate, when attached to the violin, to extend over the tail piece as shown in Fig. 1. In the body of the 50 plate *a* is an opening *a⁴*, through which the padding, when used, is inserted, and this opening is closed by a plate *a⁵*, which may be secured by small screws *a⁶*.

The upper side of the plate *a* is provided

with a projecting rim *a⁷* along the edge, and 55 this rim is wider or higher on the outer side as at *a⁸*.

c is a pad of any suitable soft material, such as felt, along the inner side of the rim *a⁸*.

d is a covering of silk or other suitable material, preferably composed of a top-piece stitched at its edge to a strip of ribbon *d'* which is cemented or otherwise secured to the outer face of the rim *a⁷ a⁸*.

e is a padding of swan's down, or other 65 soft material, filling the space between covering *d* and the base piece, which may be introduced through the opening *a⁴* before the plate *a⁵* is applied. This padding may be omitted, in which case the opening *a⁴* and 70 plate *a⁵* are unnecessary.

f is a second bracket member having at its lower end an angular flange *f''* and provided in the upper part with a longitudinal slot *f'*.

f³ is a pivot stud extending through the 75 slot *f²* and engaging a pivot hole *b²* in the bracket member *b*. The pivot stud *f³* has a head *g* on the inner end and the outer end, which projects through the pivot hole *b²*, is threaded to receive a nut *g'*. Thus the pivot 80 stud is held in place and the threaded nut *g'* when tightened will clamp the bracket members *b* and *f* together. The object of thus pivoting the bracket members together is to enable the clamping flanges *b'* and *f''* to adjust 85 themselves to the non parallelism of the upper and lower faces of the instrument. The upper and lower faces of a violin are not perfectly parallel at the point where the clamp is applied and to secure a perfect 90 clamping action with clamping flanges of substantial length the flanges must assume a non parallelism corresponding to that of the edge of the instrument. This is permitted by the pivotal connection of the 95 members *b* and *f*, and when they have assumed the proper angular inclination or degree of non parallelism they are secured in that position by tightening the nut *g'*.

To enable the clamps to be moved to and 100 from one another to engage the edge of the instrument and to be clamped thereon, the pivot stud is made movable longitudinally in the slot *f²*. For this purpose I prefer to employ a vertical screw *h* journaled in the 105 lower flange *f'* of the bracket member *f* passing through a threaded hole in the pivot stud *f³*. By turning this screw—for which

purpose a small arm *h'* may be provided—
the clamp may be opened and closed. It
will be noted that the adjustment of the
pivot stud *f*⁸ to open or close the clamp does
5 not affect the freedom of the clamping mem-
bers to adjust themselves to the non parallel-
ism of the edges of the instrument.

I have shown the lower bracket-member *f*,
provided with a lateral arm *i*. This is for
10 the purpose of attaching a shoulder rest,
and may be omitted when the shoulder rest
is not employed.

The ledge *a*⁸ on the outer side of the rest
forms a firm hold for the chin, the point of
15 which will rest on the soft cushion-surface,
while the under side of the chin will rest
upon the soft padding strip *c*. Both the
cushion-surface and the padding strip *c*
20 being soft will adapt themselves to the con-
formation of the chin, while the ledge *a*⁸
being rigid will insure a firm hold.

The offset *a*⁸ enables the rest to be placed
nearly in line with the strings so that the
instrument may be held in the proper posi-
25 tion to secure the best execution.

A removable cap or cover *r* of cloth or
other suitable material may be placed over
the cushion *d* to protect it from becoming
soiled. This may be removed and washed.

30 What I claim as new and desire to secure
by Letters Patent is as follows:

1. A chin rest for musical instruments,
consisting of an upper cushioned chin rest
portion having a clamp member adapted to
35 rest on the upper face of the instrument, a
flanged clamp member adapted to fit under
the lower face of the instrument, a pivotal
connection between said clamp members to
40 permit their clamping faces to adjust them-
selves to the non parallelism of the upper and

lower faces of the instrument, and means to
secure said clamps in adjusted position.

2. A chin rest for musical instruments,
consisting of an upper cushioned chin rest
carrying a bracket member *b* adapted to be 45
clamped on the upper face of the instrument,
the vertically slotted bracket member *f* having
a flange adapted to be clamped on the
lower face of the instrument, and a pivot
stud extending through the slot in said 50
member *f* and engaging the other member.

3. A chin rest for musical instruments,
consisting of an upper cushioned rest carrying
a bracket member adapted to be clamped
on the upper face of the instrument, a second 55
bracket member having a flange adapted to
be clamped on the lower face of the instru-
ment, one of said bracket members being
slotted longitudinally, and a pivot stud ex-
tending through the slot of said slotted 60
member and engaging the other member.

4. A chin rest for musical instruments,
consisting of an upper cushioned rest carrying
a bracket member adapted to be clamped
on the upper face of the instrument, a second 65
bracket member having a flange adapted to
be clamped on the lower face of the instru-
ment, one of said bracket members being
slotted longitudinally, and a pivot stud ex-
tending through the slot of said slotted 70
member and engaging the other member.

In testimony of which invention, I here- 75
unto set my hand.

JAMES W. HUGHES.
